(57) **CLAIM**

We claim the ornamental design for a punch tool, as shown and described.

DESCRIPTION

FIG. 1 is a perspective view of our new design for a punch tool;

FIG. 2 is another perspective view thereof;

FIG. 3 is a bottom view thereof;

FIG. 4 is a side view thereof, the opposite side view being a mirror image thereof;

FIG. 5 is a top view thereof;

FIG. 6 is a front view thereof;

FIG. 7 is a rear view thereof;

FIG. 8 is a perspective view of a second embodiment of our new design for a punch tool;

FIG. 9 is another perspective view thereof;

FIG. 10 is a bottom view thereof;

FIG. 11 is a side view thereof, the opposite side view being a mirror image thereof;

FIG. 12 is a top view thereof;

FIG. 13 is a front view thereof; and,

FIG. 14 is a rear view thereof.

The broken lines showing the rear end of the punch tool form no part of the claimed design.

1 Claim, 14 Drawing Sheets
